UNITED STATES PATENT OFFICE.

EDWARD C. COSTON, OF SKIDMORE, MISSOURI.

MACHINE FOR FORCING GEARS OR OTHER ARTICLES FROM A SHAFT.

Application filed October 4, 1920. Serial No. 414,659.

To all whom it may concern:

Be it known that I, EDWARD C. COSTON, a citizen of the United States, residing at Skidmore, but living in the county of Holt 5 and State of Missouri, have invented new and useful Improvements in Machines for Forcing Gears or Other Articles from a Shaft, of which the following is a specification.

10 This invention relates to a machine capable of forcing a shaft from a device attached thereto and more particularly to my copending application Serial No. 414,658 filed October 4, 1920.

15 The primary object of this invention is to simplify the gripping mechanism so that the same may be quickly associated with the device to be forced from the shaft.

An object of the invention is to provide 20 specially designed hooks that may readily engage behind a pulley and hold the same against movement during the forcing of the shaft from the pulley by my improved mechanism.

25 Another object of the invention is to provide means capable of generating excessive power for forcing a shaft in a direction to be removed from a device secured thereto in combination with means for holding the device against movement.

30 A feature of the invention is the novel manner of constructing the hooks and associating same with the frame so that the same may be quickly moved into position to properly engage the device to be removed.

With these and other objects in view the invention will be better understood from the following detailed description taken in connection with the accompanying drawings 40 wherein:

Fig. 1 is a side elevation of the machine.

Fig. 2 is an end elevation.

Fig. 3 is a top plan view.

Fig. 4 is a sectional view.

45 Fig. 5 is a detailed sectional view of the worm.

Fig. 6 is a detailed sectional view illustrating how the hooks are detachably connected with the frame.

50 Fig. 7 is a sectional view through one end of the worm.

Again referring to the drawings illustrating one construction of my invention the numeral 1 designates a frame consisting of the 55 front upright 2 and rear upright 3 connected by the sides 4. Slidably supported by the

uprights but keyed thereto, as illustrated at 5, is a plunger, shown in this particular case as a worm 6. This worm is moved by the sleeve 7 screw threaded thereto and having a gear 8 meshing with the drive gear 9 that in turn is connected to a shaft 10. This shaft 10 may be operated in any suitable manner but for the purpose of illustration I have shown the handle 11 so that the gears 65 may be manually operated. As far as I have proceeded it will be seen that by operating the handle 11 the sleeve will be rotated through the gear connection thereby giving longitudinal movement to the plunger or 70 worm. It will also be noted that the worm is held against rotational movement due to the keyed connection, therefore, the end of the plunger is more properly associated with the shaft 12 that is to be forced from the 75 pulley 13 or other device. To increase the effective engagement between the end of the shaft 12 and the worm a specially designed pin 14 may be detachably mounted in the socket 15 formed into the end of the worm. 80 In this particular instance I have illustrated a plurality of devices detachably connected to the front upright so as to readily swing into position to effectively engage the device that is to be forced from the shaft. In this 85 particular instance I have illustrated the pulley 13 and, therefore, I provide hook member 16, the hook portion 17 of which engage around the peripheral portion of the pulley. The opposite ends of the hooks are 90 bifurcated and pivotally connected to the bolts 18 as illustrated at 19. These bolts 18 are clamped to the uprights by the nuts 20. Any number of bolts may be distributed around the front upright so that various 95 devices may be detachably secured thereto, depending upon the work to be performed.

From the foregoing description taken in connection with the accompanying drawing it will be apparent that I provide a machine 100 of such a character that the same may be readily associated with various devices connected to a shaft so that said devices may be mechanically forced from the shaft.

It is, of course, to be understood that the 105 device that is connected directly to the pulley may be constructed in various other manners than illustrated and besides the device may be used in combination with other forms of power devices for forcing a shaft 110 in longitudinal direction and, therefore, I do not desire to be limited in any manner.

except as set forth in the claim hereunto appended.

Having thus described my invention what I claim is:

5 A machine of the character described comprising a frame, pressure exerting means supported by the frame, bolts removably

mounted in holes in the frame, nuts on the bolts engaging opposite sides of the frame for clamping the bolts to the frame, and a 10 plurality of hooks each having a pivotal connection with a bolt.

In testimony whereof I affix my signature.

EDWARD C. COSTON.
